UNITED STATES PATENT OFFICE.

ADOLPH S. ELLISON, OF NEW YORK, N. Y.

DESIGN FOR TRIMMING.

SPECIFICATION forming part of Design No. 21,793, dated August 23, 1892.

Application filed July 14, 1892. Serial No. 440,076. Term of patent 3½ years.

To all whom it may concern:

Be it known that I, ADOLPH S. ELLISON, a citizen of the United States, residing at New York city, in the county and State of New York, have invented and produced a new and original Design for Trimming, of which the following is a specification, reference being had to the accompanying drawing, forming part thereof, which represents a plan view of a piece of trimming embodying the features of the design.

The design consists of a series of connected figures A, approximating in general contour

that of a diamond. The individual diamond figures are formed from groupings of return lines *a*, and the return lines are crossed by lines *b*, produced with cord or cable-like effect, the cable lines losing themselves in the return lines at intervals.

I claim—

The design for trimming, substantially as herein shown and described.

ADOLPH S. ELLISON.
